UNITED STATES PATENT OFFICE.

HANS H. HANSEN, OF CHICAGO, ILLINOIS, ASSIGNOR TO THE CHICAGO EYE SHIELD CO., OF CHICAGO, ILLINOIS, A CORPORATION OF ILLINOIS.

EYE-GUARD.

1,099,147.

Specification of Letters Patent.

Patented June 2, 1914.

Application filed October 22, 1910. Serial No. 588,561.

To all whom it may concern:

Be it known that I, HANS H. HANSEN, a citizen of the United States, residing at Chicago, Cook county, Illinois, have invented 5 certain new and useful Improvements in Eye-Guards, of which the following, taken in connection with the drawing, is a description.

My invention has for its object the production of an eye guard designed to be used by persons exposed to the wind, dust, and other conditions of the elements making protection for the eyes and face necessary.

My invention is particularly desirable for 15 use by engineers and those in like positions where a sudden change from the cold temperature outside to the warm temperature inside of an engine cab will cause a vapor to 20 form almost instantly on the lenses of the eye guards, thus temporarily obscuring the vision. This objection I am able to overcome, by the construction hereinafter set forth, and which, together with other improvements and advantages will be more fully 25 explained.

In the accompanying drawings forming part of this specification I have illustrated the principle of my invention in what I now consider the preferred form of construction, 30 and in these drawings Figure 1 is a front elevation of an eye guard embodying my invention; Fig. 2 is a cross section taken on line 2—2 of Fig. 1 looking in the direction of the arrows; Fig. 3 is a front elevation of 35 one half an eye guard with a portion of the lens and lens holding frame broken away to show the frame and attachment secured thereto in section; Fig. 4 is a modified form of construction. Figs. 5 and 6 are respectively a plan view and side elevation of 40 another form of construction.

In Fig. 1 of the drawing A represents a frame of material which shall be sufficiently flexible to conform to the features of the 45 face, such for instance as leather, which has a binding a around the outer edges thereof. In this instance the frame A is made to fit over the eyes only, but as is obvious it may be made large enough to cover the whole 50 face if desired. The eye guard is held in position by an elastic band a' which extends around the head of the wearer. The frame A is provided with the usual apertures A' through which the lens holding frames B 55 are extended, and which are preferably al-

though not necessarily held in position by frictional engagement. The lens holding frames B are preferably constructed of rings of metal of any kind suitable for the purpose, which may be either round or oval, and 60 which are provided with a circumferential groove b for engaging and holding in place the lenses b' , b' . In the periphery of the lens holding frame B is a sight opening C, which is preferably arranged to open to 65 toward the center of the eye shield, but may be arranged at any other point in the line of vision. A movable cover C' having an elongated opening c therein is pivotally secured at c' to the outside of the periphery of 70 the lens holding frame. One end of this cover c' is bent at right angles to the cover to form a lip or projection, by means of which the cover may be moved to open or 75 close the opening C.

In Fig. 4 I have shown a modified form of construction in which a round lens is used and the lens holding frame is round. In this construction an aperture d is provided in the lens holding frame. D is a cover having an 80 aperture d' therein. A lip or projection d^2 is provided by means of which the cover may be moved so that the aperture d' registers with the aperture d to open the same, or may be moved to the position shown in the drawing when the aperture in the lens holding frame will be closed. A cord or wire d^3 or other securing means engages each end of the cover D and extends around the lens holding frame D' as shown in Fig. 4. This 85 holds the cover or shield D securely in position and allows it to be easily and readily moved in either direction.

Persons who wear eye guards are often inconvenienced by vapor which immediately 95 forms upon the lenses as the wearer changes from one atmosphere to another, this vapor being sufficient at times to entirely obstruct the vision. Especially to engineers is this a serious difficulty, but by the use of the eye 100 guards herein described the wearer simply moves the cover over the aperture C and directs his line of vision through the opening.

In the construction of these eye guards I 105 prefer to make the opening in the lens holding frame over the right eye, but it is obvious that it may if desired be made in both frames. In each of the frames shown I have provided movable covers, but these covers may if desired be dispensed with entirely if 110

the wearer be not exposed to dust, etc., the purpose being to provide a guard having a lens frame projecting away from the face, which frame is provided with a sight opening to be used in emergency.

In the form of construction shown in Figs. 5 and 6 I employ a round lens holding frame E which is provided with an opening E' and between said opening and the upwardly extending flange e at the bottom of the frame is a circumferential groove e'. A cover E², shaped to conform to the periphery of the lens holding frame closes the opening E' when it is not desired to use the same, and engaging each of the lower corners of this cover as shown in Fig. 6 is a wire e² which has one or more loops e³ formed in the same which are adapted to be tightened for the purpose of taking up any slack in the wire in order to make it fit closely around the frame. These loops also serve as means by which the wire may be moved from right to left to move the cover E' to open the aperture E.

25 I claim:—

1. An eye guard having a flexible frame, lens holding rings in said flexible frame which extend at right angles thereto, and are held in place by frictional engagement in said frame, each of said rings having a sin-

gle observation opening in the peripheral face thereof, and an adjustable cover for closing said opening, substantially as described.

2. An eye guard having a circular eye 35 piece provided in a side with an observation opening, a cover for protecting said observation opening, and a ring encircling the eye piece connected with the cover to retain the latter in place.

3. An eye guard having a circular eye piece provided in a side with an observation opening and having an annular groove forming a seat, a cover for said observation opening, and a ring fitted in said seat and connected with the cover.

4. An eye guard having a circular eye piece formed in a side with an observation opening, a cover for said opening, and a ring encircling said eye piece and connected 50 with the cover and provided with a projecting portion forming a finger piece.

In testimony whereof I have signed this specification in the presence of two subscribing witnesses.

HANS H. HANSEN.
